ACCELERATOR PEDAL DEVICE

George A. Rubisow, New York, N. Y.

Original application August 30, 1940, Serial No. 354,891. Divided and this application September 3, 1943, Serial No. 501,099

8 Claims. (Cl. 74—513)

This is a divisional application of U. S. Patent application Serial #354,891, filed under date of August 30, 1940, relating to an improvement on accelerator pedal device.

This invention provides a new embodiment of this invention which will more fully appear from the following description when the same is read in connection with the accompanying drawings and the appended claims. It is to be expressly understood, however, that the drawings are for purposes of schematic illustration only and are not intended as a definition as to the design or the limits of the several aspects of this invention.

All figures represent different aspects of this invention in simplified and diagrammatical form of illustration. In the drawings, wherein like reference characters refer to like parts throughout the several views:

Figure 1 is a longitudinal side-view of an embodiment of the device and the accelerator pedal.

Figure 2 is a plan-view of Figure 1.

Figures 3 and 4 are cross-sectional views with parts broken out of a guiding-means.

Figure 5 is another longitudinal side-view of an embodiment of the device and the accelerator pedal.

Figure 6 is a plan-view of Figure 5.

Figure 7 is a cross-sectional view of Figure 5.

Figure 8 is a cross-sectional view of the guiding-means of Figure 5.

Figure 9 is another longitudinal side-view of an embodiment of the device and the accelerator pedal.

Figure 10 is another longitudinal side-view of an embodiment of the device and the accelerator pedal.

Figure 11 is a plan-view of Figure 10.

Figure 12 is a plan-view of another embodiment of the device.

Figure 13 is another longitudinal side-view of an embodiment of the device and the accelerator pedal.

Figure 14 is a cross-sectional view of Figure 13.

Figure 15 is a cross-sectional side view with parts broken out of a shoe support as shown in Figure 12.

Figure 16 is a plan-view of an element of a caterpillar chain connection.

Figure 17 is a longitudinal side-view of an embodiment of the device and the accelerator pedal.

Figure 18 is another longitudinal side-view of an embodiment of the device and the accelerator pedal.

Figure 19 is another longitudinal side-view of

an embodiment of the device and the accelerator pedal.

Figure 20 is a plan-view of Figure 19.

One embodiment of this invention is illustrated on Figure 1. A support 64, having a curved surface or a flat surface on which the sole of the shoe (or, if desired, both sole and heel) rests, or which may be contacted by the tip of the sole or by the heel, between the heel and the sole, as shown on the figure, preferably in such a manner that heel H rests freely on floor 66 so that the weight of the foot creates a friction between the heel and the floor, which friction, in a majority of cases, is more than sufficient to maintain, free of any muscular exertion, support 64 in any operative position in which it is placed.

Support 64 may be rigidly affixed or may be pivoted at 67A as shown on Figures 1, 2, 10 and 19 or may form one piece with the operative rod 65 which is interconnected by means of two or more guiding elements, preferably rollers, to guide-means G1 and G2. The guide-means G1 may be affixed to the pedal P by mechanical means such as screws, balls, clips, or by glue or cement, or G1 may be one piece with the pedal or the pedal itself may have a suitable surface which may be considered as serving for or substituting for the said guide-means G1. Guide-means G2 is mounted rigidly in respect to the floor and has substantially the same horizontal contour as G1. Such an arrangement is one of the most convenient. The two guide-means G1 and G2 are operatively connected, one with the other, by means of a device D, as shown on Figures 1, 2, 7, and 10.

Rod 65 should preferably but not obligatorily be articulated in respect to frame 67 on which rollers R1, R2, or any other combination of rollers is mounted. This articulation may be a pivot or any other form of articulation, in particular, a ball-like articulation 69, as shown on Figure 4. It is preferable that support 64 be provided with at least one roller 70 or a plurality of rollers mounted close to the free end of support 64 or as near as possible thereto, whereby when heel H pushes support 64 to and fro, rod 65 operates the throttle by pressing down the pedal P which returns automatically to its original position when the foot is released by the spring urging the pedal upward. The pedal P is generally mounted at an upward angle of about 45 degrees.

A still more simplified embodiment is shown on Figures 5, 6, and 7 wherein rod 71 is rigid with support 71A on which rollers R1 and R2 are mounted. To facilitate the displacement of the

rollers, a strip of friction-diminishing means such as metal, "Bakelite," glass, etc., may be mounted on the passageway of the rollers during their displacement. Such friction-diminishing means may also be made of a bent metal or stamped out from any plastic 72, Figs. 5, 6 and 7, and be also provided with small guide-means in the form of an extending edge 73 to guide rollers 70 so that the device D, Figure 7, may not displace itself either to the right or to the left with respect to its longitudinal axis. Means 72 may also be provided for an arrangement of some other kind. It is, however, advisable but not obligatory, that the area in which the heel contacts the floor be provided with friction-augmenting means such as leather, rubber, suitable textile, or even metal if not very smooth. This area may be in the same plane as the aforementioned friction-diminishing means, or slightly above or below, as shown on Figures 2, 14 and 15.

Rods 65 or 71 may be mounted not only on one side, as illustrated on Figure 2, but on both sides of the support 64, or the support itself may form the two rods, as shown on Figures 5, 6 and 7.

Instead of rods 65 or 71, each rod, or a pair of rods, may consist of a two-part rod, 73 and 74, pivotally connected by means of 75. Rod 74 may also be pivotally connected by means 76 to the frame 67 of the rollers. Support 64 may be mounted on one or more rollers 70A and 70B, or on a pair thereof.

A "caterpillar" connection 77 may be mounted in one row as shown on Figure 11 or in a double row as shown on Figure 12.

Friction-diminishing means 79 may consist of two small smooth-surfaced strips 79A and 79B as shown on Figure 12 with friction-augmenting means 81 mounted between them to increase the friction between the heel (or the sole) and the floor. Figures 12 and 13 particularly show one guide means 100 having a long extending guide edge 101 rigidly affixed to the pedal P and another guide means 102 having an extending guide edge 103 rigidly affixed to the floor 104. An angle 105 is formed between the edges 101 and 102 (on Fig. 13), third guide means are 81-79A-79B, the pusher member is 106, the first guide edge having an upper side edge 109 and the second guide edge having an under side edge 110. A flexible member 111 is mounted through a pivot 67A to the support member on which the rollers 107, 107A and 108 are mounted.

Still another embodiment is illustrated on Figures 17 to 20 wherein a flexible support in one unit 82, Figure 18, replaces the support 64 and the rod or rods 65 of Figures 1 and 6. This flexible support 82 may be manufactured from a flexible sheet metal or flexible plastic, such as Celluloid, rubber-containing textiles, leather, impregnated with Celluloid materials, etc.

To assist the operation of support 82, Figure 8, a roller 84 or suitable guide-means affixed to guide-member 84 may be provided, as shown on Figure 15, rigid in respect to the floor. The floor may be provided with a device composed of 79A, 79B and 81, as shown on Figure 12.

For this purpose, these friction-diminishing and friction-augmenting means must be so mounted that part 81 is slightly below or somewhat above 79A, 79B and 81 as shown on Figure 17, in order to permit the sides of support 84 to slide with greater friction between the heel and part 81. This is shown on Figure 15 wherein the friction-diminishing means have a downward bent part 84 on the upper side of which part is affixed

friction-augmenting means 81. If desired, part 84 may itself have a rough surface to provide the friction-augmenting means.

The upper surface 80 of the pusher member 106 (as shown in Fig. 13) may be provided with a sponge rubber layer or a layer of any type of compressible substance.

The embodiment as shown on Figures 10, 11, 12, 13, 14, 16, shows the connection previously described as rod 65 or support 64 or rods 73 and 74, replaced by a plurality of small links 77, aforementioned, pivotally interconnected between themselves, the pivotal displacement of which, if desired, may be limited as illustrated on Figure

15 16, wherein the link 77 can only move limitedly with respect to 77A and 77B, and so on. Instead of a link, "caterpillar" chains or bicycle chain may be employed. One part of the "caterpillar" chain is pivotally or rigidly affixed to support 67

20 provided with rollers. The other part of the "caterpillar" chain may be provided with a support 78 on which the shoe rests and so arranged, preferably, that the heel rests on the floor, as shown on Figures 10 and 11, and the sole of the shoe

25 lightly touches support 78. Practically the whole weight of the foot is thus transmitted through the heel of the shoe to the floor whereby a friction engagement is created sufficient to maintain the device D in its required operative position, without pressure. The driver is accordingly caused no exertion and consequently experiences little or no hardship in maintaining the throttle in the required position. To permit a more ready

30 displacement of the "caterpillar" chain 77 shown in exaggerated dimension, on Figure 11, a friction-diminishing band of metal or plastic 79 may be provided below the "caterpillar" chain 77, or if deemed more expedient, above it, as depicted in 80 on Figures 12, 13 and 14.

35 40 If desired, roller 83 may be affixed at the end of 84 and another roller 85 provided below support 82 as shown on Figure 18. Also, layer 82 may be provided with friction-augmenting means 86 on its upper side, and rollers 87 and 88 may both be affixed by their own respective supports to the floor, or to the friction-diminishing and friction-augmenting devices 70A, 79B, 81 as shown on Figures 19 and 20.

45 50 All the parts composing the various embodiments of this device, described herein, may be manufactured from metal, wood, or any variety of plastic, specifically such plastics as "Bakelite," "Monsanto" plastics, etc.

Having now particularly described and ascertained the nature of my said invention and in what manner the same is to be performed, I declare that what I claim is:

55 60 1. A device for actuating an accelerator pedal of a vehicle, comprising a first guide-means rigidly affixed with respect to the floor and having at least one runway provided aside of the longitudinal symmetry axis of said pedal, a second guide means being rigidly affixed with respect to the said pedal and having at least one track aside of the said axis of said pedal, said runway and said track being operatively interconnected with each other through the intermediary of a third means, said third means operatively interconnecting the said track and said runway during its displacement along said accelerator pedal, and a pusher-member attached to the said third means through the intermediary of a flexible interconnection, one end of which is attached to the said pusher-member and the other end of which is attached pivotally to the

said third means, whereby when the said pusher-member is pushed to and fro, said accelerator pedal is actuated.

2. A device for actuating an accelerator pedal of a vehicle, comprising a first guide-means rigidly affixed with respect to the floor and having at least one runway provided aside of the longitudinal symmetry axis of said pedal, a second guide means being rigidly affixed with respect to the said pedal and having at least one track aside of the said axis of said pedal, said runway and said track being operatively interconnected with each other through the intermediary of a third means, said third means operatively interconnecting the said track and said runway during its displacement along said accelerator pedal, and a pusher-member attached to the said third means through the intermediary of a flexible interconnection, one end of which is attached to said pusher-member and the other end of which is attached pivotally to said third means, said flexible interconnection being a "caterpillar" chain.

3. A device for actuating an accelerator pedal of a vehicle, comprising a first guide-means rigidly affixed with respect to the floor and having at least one runway provided aside of the longitudinal symmetry axis of said pedal, a second guide means being rigidly affixed with respect to the said pedal and having at least one track aside of the said axis of said pedal, said runway and said track being operatively interconnected with each other through the intermediary of a third means, said third means being able to operatively interconnect the said track and said runway during its displacement along said accelerator pedal, and a pusher-member attached to the said third means through the intermediary of a flexible interconnection, one end of which is attached to the said pusher-member and the other end of which is attached pivotally to the said third means, said flexible inter-

connection being a thin plate made of elastic material.

4. A device for actuating an accelerator pedal of a vehicle comprising a first guide-means rigidly affixed with respect to the floor and having at least one runway provided aside of the longitudinal symmetry axis of said pedal, a second guide means being rigidly affixed with respect to said pedal and having at least one track aside of said axis of said pedal, said runway and said track being operatively interconnected with each other through the intermediary of a third means, said third means operatively interconnecting the said track and said runway during its displacement along said accelerator pedal, and a pusher-member attached to said third means through the intermediary of a flexible interconnection, one end of which is attached to the said pusher-member and the other end of which is attached pivotally to said third means, said pusher-member being provided on its free end with a roller contacting the said floor, whereby when the said pusher-member is pushed to and fro, the said roller rolls to and fro and the said accelerator pedal is actuated.

5. A device as set forth in claim 1 wherein the said pusher-member is provided on its top with a layer of rubber-sponge.

6. A device as set forth in claim 1 wherein the said pusher-member is provided on its top with a layer of compressible substance.

7. A device as set forth in claim 1 wherein friction-augmenting means are provided on the displacement area of the heel of the shoe resting on the said pusher-member.

8. A device as set forth in claim 1 wherein friction-diminishing means are provided on the displacement area of said pusher-member and friction-augmenting means are provided on the displacement area of the heel of the shoe resting on the said pusher-member.

GEORGE A. RUBISSOW.
